US0D1098138S

(12) **United States Design Patent** (10) **Patent No.:** **US D1,098,138 S**
(45) **Date of Patent:** **** Oct. 14, 2025**

(54) **DISPLAY SCREEN OR PORTION THEREOF WITH GRAPHICAL USER INTERFACE**

(71) Applicant: **ILLUMINA, INC.**, San Diego, CA (US)

(72) Inventor: **Max Arseneault**, San Diego, CA (US)

(73) Assignee: **Illumina, Inc.**, San Diego, CA (US)

(**) Term: **15 Years**

(21) Appl. No.: **29/910,862**

(22) Filed: **Aug. 25, 2023**

(51) **LOC (15) Cl.** **14-04**

(52) **U.S. Cl.**

USPC **D14/485**

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The outermost even dashed broken lines illustrate a display screen or portion thereof and form no part of the claimed design. The remaining even dashed broken lines illustrate features of the graphical user interface which form no part of the claimed design.

1 Claim, 1 Drawing Sheet
